COMBINED VOLT-OHM-MILLIAMMETER

Thomas P. Sheehan, Chatham, N. J., assignor to Weston Electrical Instrument Corporation, Newark, N. J., a corporation of New Jersey

Application June 14, 1954, Serial No. 30,962

Term of patent 14 years

(Cl. D26—1)

Fig. 1

Fig-2

Fig-3

Figure 1 is a perspective view of a combined volt-ohm-milliammeter made in accordance with my design;

Figure 2 is a top view thereof; and

Figure 3 is a side view thereof.

I claim:

The ornamental design for a combined volt-ohm-milliammeter, substantially as shown.
